VACUUM DEVICE

Adam Khuen-Kryk, Springfield, Pa.

Original application August 24, 1929, Serial No. 388,112. Divided and this application November 7, 1936, Serial No. 109,693

2 Claims. (Cl. 15—155)

My invention relates to vacuum device. The object is to provide improved means for delivering air under pressure to the surface to be cleaned, in combination with the usual suction means.

By air under pressure is meant compressed air or air under pressure above atmosphere.

The invention comprises improved means for delivering the air under pressure to the surface to be cleaned, in close proximity to the area upon which the suction is applied.

The invention also comprises means for delivering said air under pressure through a nozzle adapted to vibrate, due to its engagement with the surface to be cleaned, and continuously throughout the entire movement of the device, either forward or backward, over the surface to be cleaned.

The object of this vibrating, or up and down, movement of the air discharge nozzle and of the air discharging therefrom into the material, is to create a disturbance or agitation of the dust or dirt in the material to be cleaned, to cooperate with the suction action and thus to secure a more thorough and complete cleaning of the article, such as carpet, rug or other fabric usually found in house furnishings.

The action of the continuous discharge of the air under pressure in lines perpendicular to the surface of the material, causes, in combination with the suction, a deeper penetration of the cleaning action, than is secured by the suction alone.

The invention also includes means whereby the area subjected to the influence of suction may be surrounded by an area subject to the projection of air under pressure, and also whereby the area subjected to the projection of air under pressure is surrounded by an area subjected to the suction, or the suction area may both surround and be surrounded by air pressure areas.

Means are provided whereby a pressure discharge nozzle may be capable of up and down movement, while another nozzle or discharge vent may be fixed relatively to the suction nozzle.

The invention also comprises improvements in details of construction.

This application is a division of application Serial No. 388,112, filed August 24, 1929, now abandoned.

Referring to the drawing which illustrates merely by way of example a suitable embodiment of the invention;

Fig. 1 is an under or bottom plan view, and Fig. 2 is a section on line 2—2 of Fig. 1.

Similar numerals refer to similar parts throughout the several views.

The chambered body 5 is provided with the suction nozzle 6 of arcuate form in communication with the outflow pipe or nozzle 7, adapted for connection with air exhausting means, not shown. This body 5 is also provided with a passage or passages 8 surrounding or flanking the nozzle 6. Said passage or passages are in communication at one end with the nipple 9, adapted for connection with a source of air under pressure, not shown. This passage or these passages 8 deliver to a number of air discharge vents 10, arranged in approximately the plane of the intake end of the suction nozzle 6, so that said vents 10, either surround or flank the said suction nozzle.

Within the suction passage 11, leading from the suction nozzle end 6 to the outflow nozzle 7, is mounted the hollow shaft 12, stepped at one end in the threaded block 13 and journaled at the other end in the threaded bearing block 14. This shaft has a projection or nipple 15 for connection with a source of air under pressure not shown. A collar 16 is provided on shaft 12 adapted to bear against the bearing block 14, so that the parts may be held in proper operative relationship and the freedom of rotative movement may be frictionally controlled by the proper adjustment of blocks 13 and 14.

Upon this shaft 12 is mounted the arcuate channeled member 17, terminating at its forward and downwardly projecting end, in a discharge nozzle 18. This nozzle end 18 is shown as provided with the row of air discharge vents 19, which are surrounded by the suction nozzle 6.

A spring 20 is secured at one end to the wall of the suction passage, with its free end in pressure engagement with the channeled member 17.

The discharge end or nozzle 18 of channeled member 17 is also provided with a number of shoes 21 in spaced relationship, having rounded under sides, to facilitate the travel of the nozzle over the surface to be cleaned.

A stop 22 is provided within the body 5 for limiting the downward movement of the channeled member 17. This stop is so proportioned and positioned as normally to maintain the discharge end of nozzle 18 slightly below the plane of the surrounding margin of the suction nozzle 6.

The nozzle end of body 5 is provided with a substantial marginal flange 23 surrounding the intake mouth of the nozzle, and also the vents 10.

and 19, to prevent the escape of air outwardly from the discharge vents, so that the flow therefrom will be through a substantial part of the material to the suction passage 11.

5 The operation of the device is as follows:

When the device is operated, the nozzle 6 and passage 11 will be under suction or below atmospheric pressure, while vents 10 and passage 8 will be under pressure above atmosphere. The vents 19 of nozzle 18, and the passage in channel member 17 will also be under pressure above atmosphere.

While the device or chambered body 5 is moved to and fro, or forward and backward, over the surface to be cleaned, the suction through nozzle 6, will tend to remove dirt and other foreign matter from the surface operated upon. The removing action however, of a normal or moderate suction, will be effective only on the surface or for a very limited extent below the surface of the material, depending of course somewhat upon the nature of the material or fabric operated upon. If, on the other hand, the suction is abnormal or too effective, it will tend to cause the device to cling to the said surface and make it difficult to move the same in the usual way, and in the case of loose rugs or the like the same are distorted or displaced.

30 by the movement of the device over the same. In accordance with the present invention these difficulties are to a large extent, if not entirely, overcome.

In accordance with the example illustrated in the drawing, air under any desired pressure above atmosphere is projected in streams or jets from the rows of vents 10 and 19. These jets or streams obviously penetrate deeply into the texture of the material, especially if the material is of any substantial thickness, as in oriental rugs 35 or velvet or similar fabrics. As this compressed air is confined within the flange 23 of the body 5, it naturally seeks the path of least resistance, that is to the suction nozzle 6. We thus secure 40 an effective push and pull upon the dirt and foreign matter in the fabric or upon the surface 45 to be cleaned in place of the simple suction which is employed by the present type of suction cleaner.

50 The projection of the compressed air or air under pressure into the fabric tends in itself to loosen or separate the dirt from the fibers of the fabric and to blow it in the direction of least resistance and the suction acting thereon facilitates this movement. In other words the combined action of 55 the continuous discharge of compressed air into the fabric, and the continuous withdrawal therefrom of said air and the dirt mixed therewith, by suction, results in an extremely effective cleaning operation.

60 It will also be noted that the pivoted channeled member 17, having the discharge nozzle 18 is spring controlled to hold the nozzle end firmly pressed against the surface to be cleaned, so that the effective projection of air into the fabric is assured. It will be noted that this pressure of the nozzle upon the fabric is a yielding pressure to permit the nozzle to ride easily over obstruc-

65

tions such as seams or tufts in the fabric while maintaining a continuous contact and a continuous discharge of air into the fabric. The slight oscillation or up and down movement of the nozzle also tends to increase the agitation of the dirt by the varying impulses of the compressed air.

It will be understood that while a spring control is considered the preferable means for securing the yielding pressure of the nozzle, a gravity 10 actuation might in some cases be employed.

While I have shown the combination of two sets of air projecting vents 10 and 19, it will be understood that either set of vents may be employed with useful results without the other set. 15

It will therefore be understood that the invention is not to be limited to the exact details of construction shown, as these may be varied within the scope of the accompanying claims.

What I claim is:

What I claim is:

1. A vacuum device comprising a chambered body having a suction nozzle having the margin of its intake opening extending in a horizontal plane, and a suction passage leading from said nozzle and having a horizontally extending portion, a compressed air discharge nozzle-member pivotally mounted within the horizontal portion of said suction passage, and at a point laterally removed from the suction nozzle end, said air discharge nozzle member being provided with a discharge orifice having the entire margin in a substantially horizontal plane and adapted for constant and yielding engagement with a surface to be cleaned and adapted to discharge compressed air to said surface in direction approximately vertical to the plane of said surface, actuating means for normally urging said compressed air nozzle against said surface and limiting means for preventing the downward motion of said discharge nozzle appreciably below the plane of said surface.

2. A vacuum device comprising a chambered body having a suction nozzle having the margin of its intake opening extending in a horizontal plane, and a suction passage leading from said nozzle, and having a horizontally extending portion, a compressed air discharge nozzle-member pivotally mounted within the horizontal portion of said suction passage and at a point laterally removed from the suction nozzle end, said air discharge nozzle member being provided with a discharge orifice having the entire margin in a substantially horizontal plane and adapted for constant and yielding engagement with a surface to be cleaned and adapted to discharge compressed air to said surface in direction approximately vertical to the plane of said surface, actuating means for normally urging said compressed air nozzle against said surface and limiting means for preventing the downward motion of said discharge nozzle appreciably below the plane of said surface, said chambered body also formed with a compressed air passage and front and rear discharge orifices connected thereto and flanking the suction nozzle.
